(57) **CLAIM**

The ornamental design for a support member for a suspended ceiling, as shown and described.

DESCRIPTION

FIG. 1 is an upper perspective view of a support member for a suspended ceiling according to the present application; FIG. 2 is a lower perspective view thereof;

FIG. 3 is a right side view thereof;

FIG. 4 is a left side view thereof;

FIG. 5 is an enlarged front view thereof;

FIG. 6 is an enlarged rear view thereof;

FIG. 7 is a top view thereof; and,

FIG. 8 is a bottom view thereof.

The broken lines in the drawings represent the boundary of the support member for a suspended ceiling in FIGS. 1-4 and 7-8. The symbolic break lines, as well as any portion of the article between the break lines, form no part of the claimed design.
